UNITED STATES PATENT OFFICE.

WILLIAM G. SCHICKNER, OF CINCINNATI, OHIO.

DESIGN FOR A CASH-REGISTER CABINET.

SPECIFICATION forming part of Design No. 18,819, dated December 18, 1888.

Application filed September 7, 1888. Serial No. 284,841. Term of patent 14 years.

To all whom it may concern:

Be it known that I, WILLIAM G. SCHICKNER, a citizen of the United States of America, residing at Cincinnati, in the county of Hamilton and State of Ohio, have invented a certain new and original Design for a Cash-Register Cabinet, of which the following is a specification, reference being had therein to the accompanying drawing.

10 My invention comprises a new and original design for a cash-register cabinet, the essential features of said design being an extended base, an inclined top or lid, and an elevated section, as clearly seen in the accompanying perspective view of such a cabinet.

15 Here A A represent the ends of the case, and B is a desk lid or top of the same, the rear portion of said case or cabinet being provided with an elevated section, C. The lower portion of the cabinet consists of an extended 20 base, D.

I claim as my invention—

The design for a cash-register cabinet herein shown and described, the same consisting of the case A A, having an inclined top, B, elevated section C, and an extended base, D. 25

In testimony whereof I affix my signature in presence of two witnesses.

WILLIAM G. SCHICKNER.
